UNITED STATES PATENT OFFICE.

WINTHROP M. CHAPMAN, OF NEEDHAM, MASSACHUSETTS.

RAILWAY BLOCK-SIGNAL SYSTEM.

1,281,515.

Specification of Letters Patent. Patented Oct. 15, 1918.

Application filed February 26, 1913. Serial No. 750,862.

To all whom it may concern:

Be it known that I, WINTHROP M. CHAPMAN, a citizen of the United States, residing at Needham, in the county of Norfolk and 5 State of Massachusetts, have invented certain new and useful Improvements in Railway Block-Signal Systems; and I do hereby declare the following to be a full, clear, and exact description of the invention, such as 10 will enable others skilled in the art to which it appertains to make and use the same.

The present invention relates to railway block signal systems and is designed particularly for use on single track electric rail- 15 ways, although certain features of the invention are not limited to use in connection with a single track road. The preferred em- bodiment of the present invention herein- 20 after described is an improvement on signal apparatus and systems heretofore patented by me, and particularly an improvement on the apparatus and system disclosed in Patent No. 865,013, dated September 3, 1907. It is to be understood, however, that except 25 as defined in the claims, the several features of the present invention are not limited to use in connection with any particular form of signal apparatus or system.

The objects of the present invention are 30 to improve the construction and arrangement of signal actuating mechanism; to im- prove the construction of the apparatus and the arrangement of the circuit connections of a signaling system employing only two 35 line wires so as to enable a car in backing out of the entering end of a block to count off a car; and to permit a car to enter a block against a danger signal and then back off of the block without interfering with the 40 operation of the signals.

With the above objects in view, the pres- 45 ent invention consists in the devices, com- binations and arrangements of parts, and the constructions and circuit connections here- inafter described and claimed, the advan- tages of which will be obvious to those skilled in the art from the following descrip- 50 tion.

Referring to the drawings:—

Figure 1 is a view in front elevation of the 55 improved form of signal apparatus illus- trating particularly the signal with its actu- ating mechanism and the mechanical con- struction of the devices for controlling the 55 operation of the signal;

Fig. 2 is a detail view illustrating the latch and associated parts which form a portion of the apparatus which permits a car to enter the distant end of the block against a danger signal without interfering with 60 the operation of the signals;

Figs. 3 and 4 are detail views similar to Fig. 2, but showing the parts in different positions;

Figs. 5 and 6 are diagrammatic views 65 illustrating the arrangement of the apparatus and circuit connections for one block of a single track electric street railway and Fig. 7 is a detail view of the signal actuating cam.

The general arrangement of the circuit connections and the general operation of the apparatus of the signaling system illustrated in the drawings is the same as that of the system illustrated in Patent No. 865,013 and 70 will be readily understood without an ex- tended detail description thereof. The sys- tem illustrated in the drawings comprises a signal apparatus at each end of a track section or block, the signal apparatus and 75 their circuit connections being duplicates of each other. The signal apparatus are con- nected by two lines wires and these line wires in connection with the trolley wire and rail are utilized to convey the currents by 80 which the signal setting and restoring magnets are energized. Trolley operated switches are provided at each end of the block, which switches are operated by cars going in both directions. Each apparatus 85 comprises a single signal and the entrance of a car on to the block causes the signal at the distant end of the block to be set at 90 "danger" and the signal at the entering end of the block to be set at "safety". The en- trance of a second car on to the block before the first car leaves the block causes an indi- cating movement of the signal at the enter- 95 ing end of the block and actuates a con- troller which prevents the restoration of the 100 signals until the last car leaves the block.

As the cars pass out of the block at the distant end, the controller at the entering end of the block is actuated, and when the last car leaves the block the signals are returned 105 to normal or "clear" position.

In the improved signal apparatus illustrated in Fig. 1, the signal consists of a semaphore arm 1 arranged to move in a vertical plane in front of a suitable background 5 and secured to a short horizontal shaft 2 suitably supported above the signal box proper. The shaft 2 is provided with a crank arm 3 which is connected by means of a rod 4 to a crank pin on a cam 5 secured to 10 a horizontal shaft in the lower portion of the signal box 6. The normal or "clear" position of the semaphore arm is that indicated in Fig. 1 in which the arm is inclined downwardly at an angle of about forty-five degrees. To indicate danger the arm is 15 designed to move to a horizontal position, and to indicate safety it is designed to move to a substantially vertical position. The semaphore arm is also designed to move from 20 "safety" to "clear" position and then return to "safety" position to indicate an actuation of the controller when a car enters the block while the signal is at "safety". The arrangement of the connecting rod 4 with relation to 25 the cam 5 and shaft 2 is such that the desired movements can be imparted to the semaphore by a rotation of the cam, a clockwise movement of the cam operating to swing the semaphore from "clear" to "danger" position, 30 and a counter-clockwise movement of the cam operating to move the semaphore arm from "clear" to "safety", and then a continued counter-clockwise movement operating to swing the arm back from "safety" 35 to "clear" position. The semaphore arm thus has three different positions and these three positions correspond to four positions of the cam 5. To actuate the cam 5 so as to move the semaphore arm to the desired positions when cars enter and leave the block, 40 two levers, 6 and 7, are provided, centrally pivoted on studs projecting from the back of the box casing and provided at their inner ends respectively with rolls 8 and 9. These 45 rolls engage a groove 10 formed in the cam and so shaped that when the outer end of the lever 7 is raised the cam is rotated counter-clockwise and when the outer end of the lever 6 is raised the cam is rotated clockwise. When the outer ends of both levers 6 and 7 are down, as indicated in Fig. 1, the 50 two rolls 8 and 9 are near the center portion of the cam and the semaphore arm is in the "clear" position. As will be obvious from 55 an inspection of the figure, the upward movement of the outer end of lever 6 will cause the roll 8 to move down the right hand portion of the cam groove and swing the cam in a clockwise direction to move the 60 semaphore arm to "danger" position. During this movement of the cam, the roll 9 remains at rest and travels in a substantially concentric portion of the cam groove. In like manner, starting with the parts in the

position illustrated in Fig. 1, if the outer 65 end of the lever 7 is raised the roll 9 travels along the left hand portion of the cam groove 10 and the cam 5 is turned counter-clockwise far enough to move the semaphore 70 arm to "safety" position. When the roll 9 is in its lowest position it will be located just at the outer end of the cam groove 10. If now while the outer end of lever 7 still remains raised the outer end of lever 6 is 75 raised, the roll 8 will travel along the left hand portion of the cam groove 10 and the cam will be swung still farther counter-clockwise so as to move the semaphore arm from its position at "safety" to its "clear" 80 position. During this movement of the cam the roll 9 travels along the outer periphery of the cam beyond the end of the cam groove. The levers 6 and 7 are actuated in the same manner as the corresponding levers of the apparatus of Patent No. 865,013, the levers 85 being pivotally connected respectively to the lower ends of rods 11 and 12 projecting downwardly from the cores of magnets 13 and 14. In addition to the rolls 8 and 9 the levers 6 and 7 are also provided with rolls 15 and 16 which are arranged to engage the outer periphery of the cam 5. The shape of the outer periphery of the cam and of the cam groove 10 is such that the cam is securely locked against movement in all positions and thus tampering with the signal mechanism by manual manipulation of the semaphore arm is prevented. 95

The magnets 13 and 14, illustrated in Fig. 1, operate in the same manner as the corresponding magnets of Patent No. 865,013, magnet 13 of the apparatus at the distant end of the block being energized to set the distance signal at "danger," and magnet 14 at the entering end of the block being energized to set the signal at the entering end of the block at "safety" when the first car enters the block, and being thereafter energized each time a car leaves the block to 100 actuate the controller or to return the signals to "clear" position. In addition to the mechanism above described, there is also illustrated in Fig. 1 a magnet 17 which is energized each time a car enters the block, a pawl carrying lever 18 actuated through a 105 rod 19 from the core of magnet 17, a locking lever 20 for the core of magnet 14, and controlling and unlocking mechanism actuated by the pawl carrying lever 18 and by the rod 12 and core of magnet 14. These 110 parts have substantially the same construction and mode of operation as the corresponding parts of Patent No. 865,013. The lever 21, however, which holds the pawl 22 out of engagement with the ratchet wheel 115 when the magnet 17 is energized by the entrance of the first car on the block, is made 120 separate from the contact carrying lever 23. 125

The lever 23 is mounted upon the shaft of the ratchet wheel and is provided with a tooth which is covered by the lever 21 when the parts are in the position indicated in Fig. 1 so that the contact carrying lever 23 is not actuated by the entrance of the first car on to the block. As soon as the rod 12 is raised, however, and the signal at the entering end of the block is set, the lever 21 moves out of engagement with the pawl 22 and uncovers the tooth of the lever 23 so that the lever 23 is actuated each time a car enters the block after the signal has been set at "safety." The object of this change in construction will be explained hereinafter.

In the apparatus illustrated in Patent No. 865,013 a somewhat complicated system of contacts was provided for maintaining magnet 14 energized until magnet 17 was deenergized when cars entered and left the block simultaneously so as to insure the proper actuation of the controller. In the construction illustrated in Fig. 1 these extra contacts are done away with and a latch 24 is provided pivoted upon a stationary part of the casing and arranged to engage the inner end of the lever 26 to which the escapement pallet is yieldingly connected and which in the present construction also serves to hold the locking lever 20 out of the path of the locking shoulder on the rod 12 when the signal is returned to normal position. After the signal is set at "safety" the arm 26 is moved each time a car leaves the block to operate the escapement pallet so as to allow the ratchet wheel of the controller to move backwardly one step. The latch 24 is normally held by engagement with the core of magnet 17 in position so that it does not engage the rearwardly projecting lug on the lever 26. In case both the magnets 17 and 14 are energized simultaneously as they will be when cars enter and leave the block simultaneously, the latch 24 is released and at the same time the lever 26 is actuated so that the latch 24 swings over and engages the lug on the lever 26. The lever 26, together with the escapement pallet is thus held in the position to which it has been moved by the upward movement of the core of magnet 14 after the magnet 14 is deenergized, and remains in this position until the magnet 17 is deenergized. The ratchet wheel of the controller is thus moved forward a step when the magnet 17 is energized, but is not retained in this position by the pallet and is allowed to return to its former position. The engagement of the latch 24 with the lever 26 therefor insures a proper actuation, which in effect is no actuation at all of the controller when cars enter and leave the block simultaneously.

Referring now to Figs. 5 and 6, it will be seen that the circuit connections and contacts

have the same general arrangement as those of Patent No. 865,013, but that certain changes have been made tending toward simplicity and efficiency of operation. It is believed that the arrangement of the circuits and contacts will be sufficiently understood from the following description of the operation of the apparatus as a whole when cars enter and leave the block. In Fig. 5 the apparatus at one end of the block is indicated at A and in Fig. 6 the apparatus at the other end of the block at B. Except for an auxiliary restoring circuit hereinafter referred to the apparatus, circuit connections, and contacts at A and B are duplicates of each other. 27 indicates the trolley wire, 28 the rail, 29 one line wire, and 30 the other line wire. Line wire 29 is connected at apparatus A to contact plate 31 on lever 6 and is connected at apparatus B to contact plate 32 on lever 7. In like manner, line wire 30 is connected at apparatus A to contact plate 32 on lever 7 and at apparatus B is connected to contact plate 31 on lever 6. Contact plate 32 at each apparatus when the signals are at "clear" position engages a contact 33 which is connected to the trolley wire through the following connections; wire 34, wire 35, magnet 13, wire 36, contact plate 37 on lever 18, contact 38 and wire 39. Line wire 29 is thus normally connected to the trolley wire at apparatus B and line 30 is normally connected with the trolley wire at apparatus A. When a car enters the block at apparatus A going toward B a contact 40 is momentarily closed at the trolley switch and a current passes through magnet 17 of apparatus A from the trolley wire 27 to the rail 28. The lever 18 is actuated and the contact plate 41 on the lever bridges the contacts 42 and 43. The closing of these contacts establishes a circuit from line wire 29 which is connected to the trolley wire 27 at apparatus B through magnet 14 of apparatus A to the rail 28 as follows: Contact plate 31, contact 44, wire 45, contact plate 46 on locking lever 20, contact 47, wire 48, contact 42 and 43, wire 49, wire 50, magnet 14 and wire 51. The core of magnet 14 is thus raised and through the rod 12 and arm 7 the cam 5 is rotated to swing the semaphore arm to "safety" position. As the core of magnet 14 rises, the locking lever 20 drops into locking position, thereby separating contact plate 46 and contact 47. This breaks the circuit of magnet 14 and the rod 12 drops until stopped by the locking lever. At apparatus B the magnet 13 is energized simultaneously with the energization of magnet 14 of apparatus A so that the signal at apparatus B goes to "danger." When the locking lever at apparatus A drops into locking position, the contact plate 46 engages contacts 52 and 53. The circuit

through magnet 13 of apparatus B is thus closed to the rail 28 from contact 46 to contact 53 and wire 54. Magnet 13 of apparatus B will thus remain energized as long as locking lever 20 of apparatus A remains in locking position. The return of the locking lever to unlocking position, however, will break the circuit of magnet 13 of apparatus B so that the return of the signal at 10 the entering end of the block to normal position will cause the return to normal position of the signal at the distant end of the block. While the signal at apparatus A is in "safety" position the contact plate 32 is in 15 engagement with contact 55, which contact is connected by a wire to wire 50, which leads to the magnet 14. The line wire 30 is thus connected at apparatus A to the rail 28 through magnet 14. When a car passes out 20 of the block at B, contact is made by the trolley switch at 56, thus connecting the trolley wire 27 to the line 30 and energizing magnet 14 at the entering end of the block. The current passes from the trolley wire 27 25 to the line wire 30 through the wire 57, contact plate 58, contact 59, wire 60 contact plate 61 and contact plate 31, which at this time is in engagement with contact plate 61. Each time a car leaves the block therefor, 30 the magnet 14 at the entering end of the block is energized, and when the last car leaves the block the signals are returned to normal position. In case a second car enters the block before the first car leaves 35 the block, magnet 17 of apparatus A is again energized. The contact carrying arm 23 is now actuated and contact plate 62 is brought into engagement with contact 63, and contact plate 37 on lever 18 is brought 40 into engagement with contact 64. This connects one terminal of magnet 13 of apparatus A to the rail through wire 65 and connects the other terminal to the line wire 29 through the wire 35, contacts 63-62, wire 45 66, contacts 53-52 and wire 67. The magnet 13 of apparatus A is thus energized momentarily and the semaphore of apparatus A is moved from "safety" to "clear" position and then back again to "safety." 50 The reason for not moving the arm 23 when the first car enters the block will now be apparent. By holding the arm 23 against movement when the first car enters the block the contacts 62 and 63 are not brought into 55 engagement and consequently the magnet 13 at the entering end of the block is not energized.

It is desirable in some instances to permit 60 a car which has entered the block to back off of the block. In such a case it is necessary that the signal controlling and unlocking mechanism be actuated by the engagement of the trolley with the trolley switch. To permit this to be done without the use of a third

line wire, apparatus A illustrated in the drawings is provided with an auxiliary magnet 68 arranged to act on the core of magnet 14. One terminal of this magnet is connected to a contact 69 and the other terminal is connected to the rail 28. The contact 69 is arranged so as to be engaged by the contact 58 when the signal at the entering end of the block is set at "safety", the contact plate 58 being engaged by an insulated portion of lever 7 as the lever swings into a position to 70 bring the contact plate 32 into engagement with the contact 55. As has been described, the contact plate 58 is connected by the wire 57 to the trolley contact 56 which is closed when a car leaves the block. After the signal at the entering end of the block has been set at "safety" therefor, a car backing out of the block will close a circuit from the trolley wire to the rail through the auxiliary magnet 68 and actuate the controlling and unlocking mechanism and thereby count off a car in the same manner that a car is counted off when it leaves the block at the distant end.

In apparatus B, as illustrated in Fig. 6, 90 the same result is accomplished without the use of an auxiliary magnet by extending the contact plate 32 on the upper side of the lever 7 so that when the lever 7 is raised, the contact plate will engage the contacts 58 and 95 55. As has been described, the contact 58 is connected to the trolley contact 56 which is closed when a car leaves the block. The bridging of the contacts 58 and 55 establishes a local or auxiliary circuit including 100 the contact 56 and the signal restoring magnet 14.

The signal system illustrated in the drawings has provision for permitting a car to enter a block against a danger signal and to 105 back out of the block without removing the trolley wheel from the trolley wire. In the arrangement shown a car entering a block against a danger signal causes the semaphore arm to return nearly to normal position, and at the same time disconnects the wire through which the apparatus at the entering end of the block is actuated to count off a car when a car leaves the block. The semaphore arm remains in its normal position until the car which has entered against the danger signal backs out of the block, when the signal is returned to its position of danger. To secure these results a latch is provided which co-operates with the lever 110 18 and with the core of magnet 13. An auxiliary magnet is also provided for actuating or controlling the operation of the latch. The latch is pivotally mounted on a stationary part of the casing at 70, and is composed 115 of two parts 71 and 72 connected by a spring 73 coiled around the pivot stud 70. The relative movement of the two parts 71 and

72 under the force of the spring is limited by a pin 74 on the part 72 and a lug 75 on the part 71. The part 71 is pivotally connected to the lower end of a rod 76, the upper end of which is connected to the core of an auxiliary solenoid magnet 97. The portion 72 of the latch is provided with rearward extensions 77 and 78 which coöperate with a pin 79 projecting from the side of the rear portion of the lever 18. The portion 71 of the latch is arranged beneath the core of magnet 13, and is in a position to be engaged by a pin 80 on the rod 11 during the upward movement of the core of magnet 13. The normal position of the latch is indicated in Fig. 1. With the latch in this position, the pin 79 on the lever 18 is at the right of the latch, and in case the magnet 17 is energized by the entrance of a car into an empty block the lever 18 will be actuated and returned to its normal position as the magnet is deenergized. When the signal is in the danger position, however, the core of magnet 13 is up, and the pin 80 is in engagement with the part 71 of the latch. The pin holds the latch somewhat above its normal position, as indicated in Fig. 2. With the latch in this position the projection 78 on the part 72 of the latch is below the pin 79 on the lever 18. When the car enters the block against the danger signal the magnet 17 at the end of the block is energized, the lever 18 is actuated, and the pin 79 passes down to the left of the projection 78 on the part 72 of the latch. The pin 79 displaces the latch somewhat to the right, and as the pin reaches its lowest position the latch swings in over the pin and holds the lever in the position to which it has been moved by the magnet 17. The actuation of the lever 18 by the magnet 17 breaks the circuit of the magnet 13, so that the core of the magnet drops. The downward movement of the core is limited by contact with the latch, so that the semaphore arm moves nearly to normal position. The core does not drop, however, far enough to bring the plate 31 on the lever 6 into engagement with the contact 44. The downward movement of the outer end of the arm 6 breaks the circuit at 31, 61, through which the controlling and unlocking mechanism at the entering end of the block is actuated by a car leaving the block, and connects the auxiliary magnet 97 in a circuit which will be closed when the trolley switch is actuated by the car leaving the block. When the car leaves the block the circuit is closed from the trolley wire 27 through the auxiliary magnet 97 to the rail 28 as follows: contact 56, wire 57, contact plate 58, contact 59, wire 60, contact plate 61, contacts 81 and 82, contact plate 83, wire 84, magnet 97 and wire 85. The energizing of magnet 97 swings the lower end of the latch to the right, so that the pin 79 escapes from the projection 78 on the latch and engages the projection 77. As soon as the trolley contact is opened the magnet 97 is deenergized, the lower end of the latch swings to the left, and the pin 79 escapes from the projection 77, allowing the lever 18 to return to its original position. This again closes the circuit of magnet 13, and the signal returns to its danger position.

The nature and scope of the present invention having been indicated, and the preferred form of the invention having been specifically described, what is claimed is:—

1. A railway block signal system, having, in combination, a signal, a cam, means for moving the cam to four different positions, and connections between the cam and the signal acting to move the signal to three different positions when the cam is moved to its four positions. 85
2. A railway block signal system, having, in combination, a cam, levers pivoted on axes parallel to the axis of the cam, pins on the levers engaging the cam acting when the levers are actuated separately to rotate the cam in opposite directions and when the levers are actuated successively to rotate the cam in the same direction, a signal, and connections between the cam and the signal for moving the signal to different positions. 95
3. A railway block signal system, having, in combination, a cam provided with a groove, levers pivoted on axes parallel to the axis of the cam, pins on the levers engaging the groove in the cam and the periphery of the cam acting when the levers are actuated successively to move the cam from normal position in opposite directions and to lock the cam against rotation in the normal position of the cam and in the positions to which it is moved, a signal, and connections between the cam and the signal for moving the signal to different positions. 100
4. A railway block signal system, having, in combination, a signal apparatus at each end of a block, means to set a signal at safety at the entering end of the block and a signal at danger at the distant end of the block when a car enters an empty block, a restoring circuit including a trolley switch contact at the distant end of the block arranged to be operated by cars leaving the block, an auxiliary circuit, means to disconnect the trolley contact from the restoring circuit and to connect the trolley contact with the auxiliary circuit when a car enters the distant end of the block against a danger signal, and means controlled by the auxiliary circuit operating when the car backs out of the block to again render the restoring circuit operative. 110
5. A railway block signal system, having, in combination, a cam, levers pivoted on axes 115
- 120
- 125

parallel to the axis of the cam, pins on the levers engaging the cam acting when the levers are actuated separately to move the cam from normal in opposite directions and

5 to lock the cam against rotation when the cam is in normal position and in the positions to which it is moved, a signal, and con-

nections between the cam and the signal for moving the signal to different positions.
